UNITED STATES PATENT OFFICE.

CLAYTON GOODLING, OF BALTIMORE, MARYLAND.

LIFE-PRESERVER.

1,285,127.

Specification of Letters Patent. Patented Nov. 19, 1918.

Application filed February 1, 1918. Serial No. 214,924.

To all whom it may concern:

Be it known that I, CLAYTON GOODLING, a citizen of the United States, residing at Baltimore, and State of Maryland, have invented certain new and useful Improvements in Life-Preservers; and I do hereby declare the following to be a full, clear, and exact description of the invention, such as will enable others skilled in the art to which it applies to make and use the same.

My invention relates to improvements in life preservers and particularly to that type having a propelling means whereby a person equipped with the life preserver may, when in the water, propel himself in the direction of land and keep himself afloat in heavy seas.

The object of this invention is the provision of a life preserver of this character which has a collapsible frame that permits the preserver to be collapsed and folded into a compact bundle or package.

Another object of this invention is to improve the construction of life preservers and to provide a pivoted frame which will permit the preserver to be collapsed when not in use.

A further object of this invention is to provide a life preserver equipped with air sacks removably secured thereto which serve to hold the preserver afloat when in water.

A still further object of this invention is the provision of a skeleton frame in which is rotatably mounted a shaft having a propeller at one end and means located in the frame and engaging the opposite end of the shaft for rotating the propeller and shaft when in the water.

Another object of this invention is to provide a frame having removably secured to the exterior air sacks, which air sacks have secured at their meeting ends a tube which has both ends open to form a ballast to hold the life preserver in an upright position when in the water.

Another object of this invention is the provision of a life preserver of this character which will be simple, practical and comparatively inexpensive in construction and one that can be manufactured and sold at a low cost.

With these and other objects in view, the invention consists in the novel combination and arrangement of parts hereinafter more fully described and set forth in the claims 55 hereto appended.

In the drawings:

Figure 1 is a side elevation of my improved life preserver as made in accordance with this invention.

Fig. 2 is a vertical longitudinal sectional view of the same.

Fig. 3 is a vertical transverse sectional view taken on the line 3—3 of Fig. 2.

Fig. 4 is an end view of the frame in 65 folded position.

Fig. 5 is a fragmentary sectional view illustrating the manner in which the air sacks are secured to the exterior of the frame.

Fig. 6 is a top plan view partly broken away.

Like numerals of reference designate corresponding parts in all the figures of the drawings.

Referring to the drawings, the numeral 5 75 indicates the life preserver in its entirety and it comprises a frame formed of wood metal or the like. The frame comprises a plurality of bowed or arcuate shaped members 6 which members are arranged in 80 spaced pairs. Each pair of bowed members 6 has one of its ends reduced and provided with alined openings 7. The free upper ends of each pair of bowed members are provided with suitable hooks 8, the purpose 85 of which will be hereinafter more fully described.

A bolt 9 is extended through the alined openings of each pair of members 6, pivotally connecting the members together to 90 permit them to be moved in the direction of each other when in a collapsed position and to be extended outwardly when in a set up position. The bolt 9 is constructed of suitable metal and includes outer sections 95 10 and an intermediate section 11. The intermediate section 11 is journaled through the openings of the members 6 and each end of the intermediate section is hinged as at 12 into the inner end of each of the outer 100 sections 10 of the bolt, as illustrated in Fig. 2 of the drawings.

It will be understood that, by virtue of the hinged connections 12, the sectional bolt permits the members to be infolded toward one another to be folded longitudinally upon one another.

Each member is provided on one side face adjacent the lower end thereof with a laterally extending lug 13, which lugs have upwardly and outwardly inclined faces 14. A plurality of links 15 are arranged in pairs, each pair being pivotally secured by one end to one pair of the members 6, as at 17, slightly above the lugs 13. The free ends of the pairs of links 15 are provided with aligned openings through which the sectional shaft 18 is adapted to extend. The sectional shaft 18 pivotally connects the pairs of links 15 together and permits them to be moved bodily upwardly when the bowed members are moved in the direction of each other. The links are adapted to be extended in a substantially horizontal plane when the said members are moved outwardly from one another and the under edges of the links rest upon the inclined surfaces 14 of the lugs 13, thus the shaft 18 is supported and the weight and strain of the shaft is equalized on the members 6 and lugs.

The sectional shaft 18, has an intermediate portion 19, and end portions 20. The end portions 20 have their inner ends hingeably connected, as at 21, to each end of the intermediate portion 19, as clearly illustrated in Fig. 2. This hinge 21 permits the shaft and bowed members 6 to be folded longitudinally after they have been collapsed in the direction of each other.

The rear end of the shaft 18 has secured thereto a suitable propeller 22 and secured to the other end of the shaft is a bevel gear 23. The bevel gear 23 is adapted to mesh with a bevel gear 24 secured to the lower end of the vertical shaft 25 which is rotatably mounted in a U-shaped frame 26. The frame 26 is adapted to be supported adjacent the forward end of the life preserver and is secured between the opposing faces of one pair of the members 6. The frame 26 is supported between the opposing faces 25 of one pair of the members 6 by suitable brackets 27 which are secured to the exterior of the arms of the frame adjacent the lower ends thereof. These brackets are adapted to coöperate with the brackets 28 secured to the opposing faces of one pair of the members 6, and the brackets 27 and 28 are removably connected together by suitable bolts 29 and nuts 30.

A bolt 31 is loosely mounted through one arm of the frame 26 adjacent the lower end thereof and beneath one of the brackets 27 and has secured to its outer end a plate 32. The plate 32 is adapted to aline with a plate 33 carried by one of the members 6 below

the bracket 28. The plates 32 and 33 are pivotally connected together as at 34 and this permits the frame to be moved in the direction of one side of the frame when the bolts 29 are removed from the brackets 27 and 28, respectively, as clearly illustrated in dotted lines in Fig. 5 of the drawings.

A bracing arm 35 is secured between the opposing faces of the arms of the frame 26 adjacent the upper end thereof and rotatably receives the shaft 25 therethrough. A bevel gear 36 is secured to the upper end of the shaft 25 and is adapted to mesh with the bevel gear 37 secured to the shaft 38 journaled in the extreme upper ends of the arms of the frame 26. The ends of the shaft 38 extend laterally beyond the side faces of the arms of the frame 26 and are secured thereto by suitable crank handles 39 through the medium of which the shaft 38 is rotated which in turn rotates the shafts 25 and 19, respectively. This rotation causes the rotation of the propeller which urges the life preserver forwardly when in the water.

The exterior of the members 6 have secured thereto a suitable covering 40 which is formed of rubberized cloth or other suitable fabric and this covering forms air sacks 41 which serve to hold the life preserver afloat when in the water.

The fabric covering 40 is formed of a doubled piece of cloth having its medial portions secured together longitudinally thereof to provide the air sacks 41 and these air sacks are adapted to be located on the opposite sides of the life preserver 6, as illustrated in Fig. 3. The air sacks 41 are equipped with suitable valves 42 whereby they may be inflated when in use.

The upper edges of the air sacks have secured thereto suitable loops 43 which are adapted to aline with the hooks 8 carried by the bowed members 6 to permit the covering to be readily and removably secured to the exterior of the members 6.

It is to be understood that the air sacks, due to their flexibility, will readily conform to the configuration of the bowed members 6, as illustrated.

The central portion of the covering 40 is adapted to engage the pivoted ends of the bowed members 6, as illustrated, and this portion 40 is provided on opposite sides of its longitudinal axis with depending flaps 44, which flaps are secured to longitudinally extending tubes 45, each end of which is provided with an opening 46 so as to permit the water to freely enter into the tube when the life preserver is placed in the water. Thus, the tube will act as a ballast to hold the life preserver righted when in the water.

The forward end of the covering 40 is closed as illustrated, and to hold it in an

extended position so as to form a bow of a boat, or substantially so, the covering is provided with a bowed member 47 which is secured therein and has its lower end terminating into an eye 48 which is adapted to be removably arranged over the end of one end section 10 of the shaft 9, as clearly illustrated in Fig. 2. A reinforcing member 49 is secured to the upper edge of the covering 10 on the interior thereof and is connected as at 50 at its medial portion to the upper end of the member 47. The ends of this member 49 are secured to the upper ends of one pair of the members 6 as at 51. Thus, it can be seen that the forward end of the covering 40 will be reinforced and held in an extended position when the device is being used as a life preserver.

A suitable hammock 52 is adapted to be suspended between the opposing faces of the members 6 through the medium of straps 53 which are secured by one end as at 54 to the edges of the hammock and have their free ends terminating into loops which are adapted to be arranged over hooks 55 carried by the opposing faces of the bowed members 6 adjacent the upper ends thereof.

The hammock 52 is adapted to be equipped with suitable straps adapted to be passed over the shoulders of a person to strap the same against his bust and abdomen. Thus, it can be seen that the device when assembled should only be approximately three and one-half or four feet long and it is only necessary to inflate the side sacks 41 in any suitable manner so that when entering the water the side sacks will keep the raft afloat and by rotating the shaft 28 through the medium of the cranks 29, the shaft 18 and propeller 22 will be rotated and the life preserver propelled in a manner similar to an ordinary boat or the like.

It will be understood that when the device is not being used the covering 40 is entirely removed from the frame and folded in a compact bundle. The frame is then collapsed by urging the bowed members in the direction of each other, the links being moved upwardly to permit of this movement and after they have been urged into clamping engagement with each other they are folded through the medium of the hinged connection of the sectional shaft and bolt; thus the device requires but a very small amount of space when not being used.

Having thus described my invention what I claim is:

1. A life preserver comprising a plurality of bowed members, a shaft journaled through said members, a propeller on one end of the shaft, a gear at the opposite end of the shaft, a frame secured to one pair of said members, a shaft journaled in the frame, a gear on the lower end of the shaft meshing with

the gear of the first named shaft, a second gear secured to the upper end of the shaft, means meshing with the gear of the second named shaft for rotating the shafts, and a covering secured to said frame and constituting floats therefor.

2. A life preserver comprising a frame including a plurality of members arranged in pairs, means for pivotally connecting each pair of the members together, a sectional shaft journaled in said members, a propeller at one end of the shaft, a gear at the opposite end of the shaft, a U-shaped frame secured to the opposing face of one pair of the members, means carried by the frame and cooperating with the gear of the shaft for rotating the shaft and propeller, a hammock removably secured to the opposing faces of the frame members, and a covering constituting floats removably secured to each pair of members, as and for the purpose specified.

3. A life preserver comprising a frame including a plurality of members, said members arranged in pairs, means for pivotally connecting the pairs of members together, a plurality of links arranged in pairs and each pair pivotally secured to each pair of the members, a shaft journaled through the members and free ends of the links for pivotally connecting the links together, said shaft and means being in sections to permit of the collapsing of the members, and means located between one pair of said members for rotating the shaft and propeller, and a covering secured to the exterior of the members and constituting air floats.

4. A life preserver comprising a plurality of members arranged in spaced pairs, a sectional bolt pivotally securing the pairs of members together, a sectional shaft, links pivotally secured to the members and journaled in the shaft, a frame pivotally secured by said members, means located in said frame and engaging the first named shaft for rotating the latter, a hammock removably secured to the opposing faces of the members, a covering removably secured to and completely inclosing the exterior of said members, said covering providing air sacks which constitute floats, and a ballast tube secured to the longitudinal axis of the covering, as and for the purpose specified.

5. A life preserver comprising a frame including a plurality of members arranged in spaced pairs, a sectional bolt pivotally securing each pair together, links arranged in pairs and each pair pivotally secured to each pair of members, a sectional shaft journaled in and pivotally securing the free ends of the links together, a propeller at one end of the shaft, a gear at the opposite end of the shaft, a swinging frame pivotally and removably secured between the opposing faces of one pair of members, means secured in the

frame meshing with the gear of the first named shaft for rotating the latter and the propeller, a covering removably secured to the exterior of the members and constituting a float therefor, a frame located in the forward end of the covering for holding the same extended, means for connecting the frame covering to the sectional bolt at one end thereof, a hammock removably secured 10 to the opposing faces of the pairs of mem-

bers, and a ballast tube secured to the longitudinal axis of the covering at the under side thereof.

In testimony whereof I affix my signature in presence of two witnesses.

CLAYTON GOODLING.
